(57) **CLAIM**

I claim the ornamental design for the comb, as shown and described.

DESCRIPTION

FIG. 1 is a bottom, front and right side perspective view of a comb of my new design;

FIG. 2 is bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines are shown for the purposes of illustrating parts of the article that form no part of the claimed design.
